(57) **CLAIM**

The ornamental design for a combined broom and dustpan as shown and described.

DESCRIPTION

FIG. 1 is a front, right and top perspective view of the broom of the combined broom and dustpan in FIG. 1.

FIG. 2 is a rear, left and bottom perspective view of the broom of the combined broom and dustpan in FIG. 1.

FIG. 3 is a front elevation view of the broom of FIG. 1.

FIG. 4 is a rear elevation view of the broom of FIG. 1.

FIG. 5 is a left side elevation view of the broom of FIG. 1.

FIG. 6 is a right side elevation view of the broom of FIG. 1.

FIG. 7 is a top plan view of the broom of FIG. 1.

FIG. 8 is a bottom plan view of the broom of FIG. 1.

FIG. 9 is an enlarged view of detail 9 in FIG. 1.

FIG. 10 is an enlarged view of detail 10 in FIG. 8.

FIG. 11 is a front, right and top perspective view of the dustpan of the combined broom and dustpan in FIG. 11.

FIG. 12 is a rear, left and bottom perspective view of the dustpan of the combined broom and dustpan in FIG. 11.

FIG. 13 is a front elevation view of the dustpan of FIG. 11.

FIG. 14 is a rear elevation view of the dustpan of FIG. 11.

FIG. 15 is a left side elevation view of the dustpan of FIG. 11.

FIG. 16 is a right side elevation view of the dustpan of FIG. 11.

FIG. 17 is a top plan view of the dustpan of FIG. 11.

FIG. 18 is a bottom plan view of the dustpan of FIG. 11.

FIG. 19 is an enlarged view of detail 19 in FIG. 11; and,

FIG. 20 is a front, left and top perspective view of a combined broom and dustpan showing my design.

The broken lines depict portions of the combined broom and dustpan that form no part of the claimed design.

The dot-dash broken lines in FIGS. 1, 8, 9, 10, 11 and 19 depict the boundaries of the enlargements that form no part of the claimed design.

1 Claim, 20 Drawing Sheets
